(No Model.)

F. BEINDORF.

TRACTION WHEEL.

No. 358,532.

Patented Mar. 1, 1887.

UNITED STATES PATENT OFFICE.

FREDERICK BEINDORF, OF LITCHFIELD, ILLINOIS.

TRACTION-WHEEL.

SPECIFICATION forming part of Letters Patent No. 358,532, dated March 1, 1887.

Application filed January 18, 1887. Serial No. 224,671. (No model.)

To all whom it may concern:

Be it known that I, FREDERICK BEINDORF, a citizen of the United States, residing at Litchfield, in the county of Montgomery and State of Illinois, have invented certain new and useful Improvements in Traction-Wheels; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to traction-engines which have the drive-wheels provided with adjustable spurs adapted to be projected beyond or drawn within the periphery of such wheels.

The improvement consists in the novel devices for adjusting such spurs in or out at will, which will be more fully hereinafter set forth, and shown in the drawings, in which—

Figure 1 is a plan view of the rear portion of a traction-engine provided with my improvement; Fig. 2, a rear end view of one side of the engine and the device attached thereto. Fig. 3 is a view, parts broken away, of one of the drive-wheels as seen from the inner side. Fig. 4 is a front view, parts broken away, of 30 the devices for setting and releasing the spur-actuating lever. Fig. 5 is a perspective detail view of the setting-lever, showing by full lines the position of the lever-projecting catch previous to its engagement with the spur-actuating lever, and by dotted lines the position of said catch when in engagement with the spur-actuating lever. Fig. 6 is a perspective detail view of the releasing-lever, showing its operation by full and dotted lines.

40 The object of the invention is to devise a simple, compact, and efficient means for projecting and withdrawing the spurs of a traction-wheel at will, and at the same time utilizing a portion of the propelling power to effect such result.

The traction-engine comprises the body A, the axle B, and the drive-wheels C, of ordinary and well-known construction. The drive-wheels are provided at stated intervals with 50 the adjustable spurs b, which are located in suit-

able openings formed through the rim of the wheel, and are connected with the ring or sleeve D, mounted loosely upon the axle or hub of wheel, so as to turn thereon by the links b'. The spur-actuating lever E is connected at its 55 inner end with the sleeve D, and its outer end passes through the keeper F, secured to the inner side of the wheel, near its periphery. The keeper comprises two sides, d and d'. The side d', which is adjacent to the body of the engine, has a notch at its rear end, forming the shoulder or stop d'', which engages with the spur-actuating lever, and holds the same when moved back the full extent of its travel by the lever-projecting catch G, pivotally connected 60 at its inner end with the setting-lever H. The spur-actuating lever is held under tension against the side d' of the keeper F by its own resiliency, or by the spring-arm e, or by the combination of both such forces. The spring-arm 70 e may form an integral part of or be separated from and attached to the lever E, and its free end rests against the side d, which forms a guide therefor in its movements.

The setting-lever H is pivoted between its 75 ends to the bracket I, secured to the body A, and its outer end passes through the keeper J, while its inner end carries the lever-projecting catch G, composed of the trip-arm g and the stay-bar or shoe g'. The trip-arm g is adapted 80 to be projected across the top of the keeper F within the path of the spur-actuating lever, and the shoe or stay-bar g', integral with and projecting substantially at right angles to the trip-arm, is adapted to travel upon the outside 85 of the keeper F and hold the trip-arm in engagement with the spur-actuating lever till the latter reaches the limit of its movement, which is when it is opposite to the notch in the rear end of the side d' of the keeper F. At this moment 90 the forward portion of the shoe or stay-bar begins to leave the keeper, when it ceases to bear against its side, and the trip-arm turns back and rides over the spur-actuating lever. That portion of the shoe between its ends and adjacent to 95 the keeper is removed to more readily permit the lever-projecting catch to disengage itself from the spur-actuating lever. The spring g'' is interposed between the body A and the lever-projecting catch for holding the latter in a nor- 100

mal position. The outer end of the lever bears against the side of the slot j in the keeper, and is held out of the way or in an operative position by the stop j' , projecting into said slot 5 from its side. It is bifurcated, forming arms h and h' , either or both of which may be elastic, so as to be compressed for clearing the stop j' when adjusting the lever from one position to another. The arms springing apart 10 will engage with the stop and hold the lever in the adjusted position.

The releasing-lever K has its outer end, which passes through a second slot, j'' , in the keeper J , similarly constructed to the outer 15 end of the lever H , and held in either position by the stop j'' . The lever itself is pivotally supported between its ends to the bracket I , and its outer end is provided with the arm k , which terminates in the cam-head k' , which is adapted 20 to be projected within the path of the spur-actuating lever and disengage the same from the shoulder d'' , when the weight of the machine upon the ends of the spurs, assisted by the spring a , will return the spur-actuating lever 25 to its normal position and withdraw the spurs.

In practice, suppose it becomes necessary to project the spurs to prevent slipping of the wheel. The setting-lever is adjusted so that the lever-projecting catch lies in the path of 30 the spur-actuating lever, which lever, engaging with said catch, is held till the wheel advances the distance of the slot in the keeper. The catch is then disengaged from the spur-actuating lever, which is held against a retrograde 35 movement by the shoulder or stop d'' . To withdraw the spurs, the releasing-lever is adjusted to throw the cam-head within the path thereof, which cam-head, as the machine advances, engages with the spur-actuating lever and dis- 40 engages the same from the shoulder or stop d'' , when the lever, returning to its normal position

by the combined action of the spring a and the weight upon the ends of the lowermost spurs, performs the desired result.

Having thus described my invention, what I 45 claim, and desire to secure by Letters Patent, is—

1. The combination, with the traction-wheel, the adjustable spurs, and the spur-actuating lever, of the setting-lever and the lever-projecting catch, substantially as and for the purpose described. 50

2. The combination of the wheel, the adjustable spurs, the spur-actuated lever, the keeper having a shoulder at one end, the setting-lever, and the lever-projecting catch composed of a trip-arm and the stay-bar or shoe, substantially as described. 55

3. The combination of the wheel, the adjustable spurs, the spur-actuating lever, and 60 the releasing-lever, substantially as and for the purpose described.

4. The combination, with the wheel having adjustable spurs and the spur-actuating lever, of the releasing-lever and the arm projecting 65 laterally therefrom and terminating in a cam-head, as and for the purpose described.

5. The combination of the wheel having adjustable spurs, the spur-actuating lever, the setting-lever, the lever-projecting catch, the 70 releasing-lever, the keeper-plate J , having two slots to receive the ends of the setting and releasing levers, respectively, and the straps projecting into said slot, substantially as and for the purpose described. 75

In testimony whereof I affix my signature in presence of two witnesses.

FREDERICK BEINDORF.
